UNITED STATES PATENT OFFICE.

AARON PARK, OF OTTUMWA, IOWA, ASSIGNOR TO HIMSELF AND THEODORE P. BAKER, OF SAME PLACE.

CAR-COUPING.

SPECIFICATION forming part of Letters Patent No. 288,105, dated November 6, 1883.

Application filed August 21, 1883. (No model.)

To all whom it may concern:

Be it known that I, AARON PARK, of Ottumwa, in the county of Wapello and State of Iowa, have invented a new and Improved Car-Coupler, of which the following is a full, clear, and exact description.

The invention consists in a draw-head provided with two link-apertures, one above the other, and with a U-shaped coupling-pin having two downwardly-projecting pins for coupling a link in the upper or lower link aperture. The bottom shank of the U-shaped coupling-pin passes through a curved slot or recess in the upper edge of a transversely-sliding bar, 15 by means of which bar the pin can be raised. A link-raising frame is held to slide vertically in the draw-head, as will be fully set forth hereinafter.

Reference is to be had to the accompanying 20 drawings, forming part of this specification, in which similar letters of reference indicate corresponding parts in all the figures.

Figure 1 is a longitudinal sectional elevation of my improved car-coupler. Fig. 2 is an end 25 view of the same. Fig. 3 is a longitudinal elevation of the sliding rod for raising the pin. Fig. 4 is a face view of the link-raiser.

The draw-head A is provided with two end 30 openings, A' A², one above the other, and each adapted to receive a usual coupling-link, B. A square or oblong frame, C, is held in a vertical slot near the outer end of the draw-head in such a manner that the upper edges of the top and bottom cross-pieces of the frame will 35 be flush with the bottom surfaces of the openings A' A². One of the sides of the frame is extended upward, and has a slot at its upper end, through which slot a handle-lever, D, passes, which rests in a transverse groove in 40 the top of the draw-head and projects from one side of the draw-head, the said lever being pivoted to the draw-head at the opposite side. By lifting the lever D the frame C will be raised, as will also the link resting on the top 45 or bottom cross-piece of the frame. The coupling-pin F is made U-shaped, and has a pin, F', projecting downward vertically from the end of each shank. The pin F is held on a vertical longitudinal slot in the draw-head. A 50 bar, G, placed edgewise, is held to slide trans-

versely in the rear part of the draw-head, and is provided at one end with a check-lug, G', and at the opposite end it is pivoted to a connecting bar or rod, H, having a handle at its outer end and passing through a vertical guide-slot in a downwardly-projecting arm, J, of the car. The bar H is provided in its bottom edge with notches a for locking the bar in the desired position on the arm J. If desired, the lower end of a lever, K, pivoted to the end of 55 the car, is pivoted to the bar H to permit manipulating the bar H from the side of the car or from the platform. The sliding plate G is provided in its upper edge with a curved slot or recess, L, shaped as shown in Fig. 3, and forming 60 a prong, L'. The same result may be attained by locating the slot in the end of the plate, in which case it will describe the arc of a large circle, its inner end curving downward. The bottom shank of the U-shaped part of the 65 coupling-pin F passes through the curved slot L, and if the plate G is drawn in the direction of the arrow a' the bottom shank of the coupling-pin will slide up the bottom curved edge of the slot, and thereby the pin will be raised 70 and the link released, whether the same is in the top or bottom opening of the draw-head. If the plate G is moved in the inverse direction of the arrow a', it permits the pin to drop; or, if the spring L', which may be dispensed 75 with, is provided, the pin will be drawn downward.

Having thus described my invention, what I claim as new, and desire to secure by Letters Patent, is—

1. The combination, with a draw-head having two link-openings, one above the other, of a U-shaped coupling-pin, having a downwardly-projecting pin at the end of each shank, substantially as herein shown and described.
2. The combination, with a draw-head having two link-openings, one above the other, of a U-shaped coupling-pin, having a downwardly-projecting pin at the end of each shank, and of a sliding plate, provided with a curved slot 95 for raising the coupling-pin, substantially as herein shown and described.
3. The combination, with the draw-head A, having the openings A' A², of the U-shaped pin F, having a downwardly-projecting pin at 100

the end of each shank, the sliding bar G, having a curved slot, L, and the frame C held in a transverse slot in the front part of the draw-head, and of the lever D for adjusting the frame C, substantially as herein shown and described.

4. The combination, with the draw-head A, having the link-openings A' A², of the U-shaped coupling-pin F F', the sliding bar G, having a curved slot or recess, L, the connect-

ing bar or rod H, having notches a a, and of the downwardly-projecting arm J, having a slot through which the bar or rod H passes, substantially as herein shown and described.

AARON PARK.
